ATTORNEY

UNITED STATES PATENT OFFICE.

JOHN L. CROSSETT, OF HINSDALE, MASSACHUSETTS.

NONRATTLING SHUTTER HOLDER.

1,410,893.

Specification of Letters Patent. Patented Mar. 28, 1922.

Application filed March 7, 1921. Serial No. 450,433.

To all whom it may concern:

Be it known that JOHN L. CROSSETT, a citizen of the United States of America, residing at Hinsdale, in the county of Berk-
shire and State of Massachusetts, has invented certain new and useful Improvements in Nonrattling Shutter Holders, of which the following is a specification.

This invention relates to improvements in combined shutter stops or holders and bumpers and its leading object is to provide a device of this kind of simple construction which will hold a blind or shutter in open position and prevent rattling.

Another object of the invention is to provide a device of this character which can be made in one piece from wire or the like so as to provide a latch keeper, a screw and a spring abutment or bumper.

With the above and other objects in view this invention relates to certain new and useful constructions, combinations, and arrangements of parts, clearly described in the following specification and fully illustrated in the accompanying drawings, in which:

Figure 1 is a side elevation.

Figure 2 is a horizontal sectional view.

Referring to the accompanying drawings 30 5 designates an attaching screw having a threaded tapered point 6 whereby the same can be forced into the window frame. The screw extends from an eye 7 and from the eye 7 the triangular shaped keeper 8 extends, one terminal of the keeper being continuous with the wire forming the eye 7 and the other terminal being connected with the shank 9 which extends through the eye and which is connected with the coil spring 10

disposed laterally of the shank 9 and providing a spring abutment or bumper.

The keeper 8 may be of any suitable shape and is designed to receive the latch carried by the swinging blind or shutter.

When the screw 5 is properly secured in place and the blind or shutter is swung into open position the latch will ride on the keeper 8 and the side of the blind will engage the end of the coil spring and the coil spring will exert a constant tension against the side of the blind to hold the latch in positive contact with the keeper and thus prevent rattling. The article is preferably made of wire in one piece and thus permits of economical manufacture and easy application.

Having described my invention, I claim:

1. A shutter holder and abutment consisting of a retaining screw or the like, a latch keeper extending therefrom, a shank 60 connected with the keeper and extending laterally thereof, and a coiled spring buffer extending from the shank in spaced relation to the keeper the screw being connected to the keeper and the shank by means of an 65 eye integral with said screw keeper and shank.

2. A non-rattling shutter holder consisting of a shank adapted to be driven into woodwork, an eye formed on the shank, a 70 stop extending from the eye and consisting of a closed loop, one end of the loop being extended through the eye and extended laterally thereof, and a coil spring formed on said extended end and projecting in the 75 direction of the loop and beyond said loop.

Signed by me at Hinsdale, Massachusetts.
JOHN L. CROSSETT.
